AUTOMATIC EXPANDING MACHINE

George W. Chalmers, Summit, Ill., assignor to
International Patents Development Company,
Wilmington, Del., a corporation of Delaware

Application July 29, 1933, Serial No. 682,839

4 Claims. (Cl. 113—18)

This invention relates to improvements in expanding machines adapted to attach together two cup-shaped sheet metal bodies by expanding the vertical walls thereof into interlocking engagement.

The invention is concerned particularly in the provision of improvements whereby machines of the above character may be used to an advantage in attaching pouring spout structures to cans.

10 In this connection, the invention contemplates as one of its objects the provision of improved and simplified means for supporting a plurality of expanding tools above the can receiving table of the machine so as to rotate therewith and to permit simultaneous vertical adjustment of said tools with relation to the table.

Another object is to provide improved means for insuring proper positioning of the can and spout beneath the expanding tool and also for 20 positioning the said spout relative to the can.

The invention is illustrated in a preferred embodiment in the accompanying drawings, wherein:

25 Fig. 1 is a side view partly in section of an apparatus constructed in accordance with my invention.

Fig. 2 is a plan view of the structure shown in Fig. 1 with parts of the upper portion of the machine broken away for the purpose of illustrating 30 underlying parts.

Fig. 3 is a vertical section taken through the machine on line 3—3 of Fig. 2, looking in the direction indicated by the arrows.

35 Fig. 4 is a fragmentary plan view of the mechanism for feeding the cans onto a rotating table of the machine.

Fig. 5 is an enlarged sectional view of a sectional expanding die which surrounds the lower portion of a plunger adapted to expand the die sections, the said parts being illustrated as positioned in a spout structure ready to expand the walls of the spout into locking engagement with the walls of a dished shape closure member.

40 Fig. 6 is a fragmentary sectional view of the lower portion of the structure shown in Fig. 5, but illustrating the die sections and plunger in their final operative positions.

Fig. 7 is a view in perspective of one of the sectional die members, and

45 Fig. 8 is a fragmentary side view of the outer end of a conveyor shown in Fig. 1.

The invention is illustrated in connection with flat sided cans 110, each having a dished closure member 111 which is crimped or otherwise suitably secured at 112 to an upstanding flange 113

surrounding the filling opening in the top of the can. The pouring spout herein shown is formed with a cup-shaped portion 114 and a lip 115. The cup portion of the spout structure is adapted to seat within the dished closure member 111. The vertical walls of the spout structure and the dished closure member are expanded to offset them as shown at 116—117 respectively in Fig. 6 to form interlocking ribs which secure the spout structure firmly in the closure member 111. 10 When the contents of the can is to be used, holes are punched in the closure member 111 opposite the holes 118—118 formed in the bottom of the spout structure.

The machine herein shown for fixing pouring spouts on the cans comprises a table 119 mounted to rotate above a supporting base 120. The table preferably consists of a plate 121 secured to the upper face of a gear 122 the latter of which is provided with a hollow hub 123 which is journaled in a suitable bearing in the upper portion of the supporting base 120. 124 designates a centrally disposed tubular shaft to which are fixed spider members 125 and 126. An arm 127 is secured to the tubular shaft and carries at its outer end a pin 128 which is slidably fitted in an opening 129 in the rotating table 119. Said arm and pin provides a connection whereby the table 119 and the spiders 125—126 will rotate in unison. This connection also permits the said spiders and said tubular shaft to be adjusted vertically with relation to the table 119 to accommodate cans of different heights. The said vertical adjustment of the tubular shaft and the spiders 125—126 is accomplished by means of a central 25 shaft 130 provided at its upper end with a spider 131 and formed at its lower end with a threaded portion 132. A bevel gear 133 is journaled in a cross member 134 and is formed with an internally threaded hub which receives the 30 threaded portion 132 of the shaft 130. A bevel pinion 135 meshes with the gear 133 and is rotated to raise or lower the shaft 130 by means of a crank 136 on the shaft 137. The shaft 130 is held from rotating by means of an arm 138 35 clamped to the shaft 130 and extending through slot 139 in the supporting base. The said clamp arm 138 serves also as a support for the rotatable tubular shaft 124. A thrust washer 140 is preferably interposed between the lower end of 40 the tubular shaft and the said clamp arm.

The spider 125 is formed adjacent its outer edge with a plurality of bearings 141 for supporting and guiding the lower portion of a plurality of expanding tools 142. These tools are 45

preferably of identical construction. It will be sufficient therefore to describe but one of them in detail. Each expanding tool consists of a die carrier 143 which is slidably supported in one of the bearings 141, the said carrier being formed at its upper end with a shoulder adapted to seat on the spider 125 to limit downward movement of the carrier and thereby prevent the expanding tool from pressing downwardly on the closure member of the can. The carrier is of cylindrical form and is provided at its lower end with an internal groove 144 which forms a supporting ledge for a plurality of pendant die members 145. The pendant die sections are formed with rounded ribs 146 adapted to be inserted in the groove 144 to provide a pivotal connection with the die carrier. There is sufficient clearance between the upper portions of the die sections to permit them to be assembled in the groove 144. Each die section is formed with a wedge surface 147 and with an external arcuate rib 148, the latter of which is pressed into the metal of the spout and closure members when the die sections are forced outwardly from the position shown in Fig. 5 to the position shown in Fig. 6 of the drawings. The said pendant die members are held in their retracted position by means of a spring 149 which seats in external grooves 150 formed in the die sections. The pendant die sections are forced outwardly by the conical lower end of a vertically movable plunger 151. The plunger extends through the central part of the die carrier 143 so that its lower end is guided by this member. The upper portion of the plunger is guided in one of the bearings 152 formed on the spider 126. Preferably the plunger is held against rotation in said bearing by means of a stop pin 153 which projects into a longitudinally extending slot 154 formed in the plunger. The said plunger is also provided with a longitudinal slot 155 near its lower end which receives a stop screw 156 which extends through the upper portion of the die carrier 143. This stop screw and slot, it will be noted, provides a lost motion connection between the plunger 157 and the die carrier 143. A coiled spring 157^a surrounds the plunger and is interposed between the upper portion of the die carrier 143 and a collar 158 secured to the plunger so that the die carrier 143 is held against the spider 125 by spring pressure when the pendant dies reach lowermost position. When the dies reach such position they are supported by the spider 125 while the plunger 157 continues its downward movement to force the pendant dies outwardly. The upper end of the plunger is provided with a clevis for a roller 159. A roller 160 is secured to the outer face of the clevis and bears on a trackway 161. The trackway extends around approximately one-third of the machine and is suspended from the top spider 131 by means of angles 162. Spacing blocks 163 are interposed between the angles 162 and the trackway. One end of the trackway is formed with a downwardly inclined portion 163^a at a location which permits the plunger 157 to be lowered by gravity sufficiently to extend the pendant dies into the cup-shaped portion of the pouring spout structure. A fixed cam member 164 is supported from the upper spider 131 at a location to engage the roller 159 of the plunger mechanism when the plungers of the machine are rotated past the said cam member.

The table 119 and spiders 125—126 are rotated by means of a pinion 165 mounted on a vertical

shaft 166 and meshing with the large gear 122. This shaft is mounted to rotate in a suitable bearing 167 on the base member. The lower portion of shaft 166 carries a bevel gear 168 which meshes with bevel gear 169 on a horizontal shaft 170, the latter of which is driven by means of a sprocket and chain connection 171 with an electric motor 172.

The cans, together with the pouring spout loosely positioned thereon, are moved onto the rotating table by means of a chain conveyor 173 and a forwarding wheel 174. The conveyor consists preferably of stationary guide members 175—176 and a chain 177 the latter of which is provided with spaced lugs 178 thereon and which move the cans toward the machine in spaced relation to each other. At or near the end of the conveyor chain the cans are engaged by the extremities of arms 179 of the forwarding wheel 174 and moved onto the table into a position whereby the cup-shaped portion of the pouring spout structure will be directly beneath one of the expanding tools.

In order to insure proper positioning of the cans on the table, provision is made for adjusting the position of the forwarding wheel with relation to the expanding tools. The hub 180 of the wheel is mounted loosely on the shaft 181. A head 182, fixed on the upper end of the shaft 181, is provided on its under side with a recess 183 adapted to receive a lug 184 which projects upwardly from the forwarding wheel. Adjusting screws 185 extend through the member 182 and engage the lug 184 to hold the wheel in any desired adjusted position.

When the spout structures are initially placed on the cans they are preferably positioned substantially at the angle indicated at A in Fig. 4 of the drawings. As the cans are fed onto the rotating table of the machine the end portion of the pouring spout lip is engaged by a fixed cam member 186 which is secured to the outer member of the conveyor guide. This rubbing engagement of the spout against the cam member insures proper alignment of the spout structure with relation to the corner of the can before the spout structure is fixed rigidly to the can. While the cans are rounding the curved portion of the outer guide member they are supported on their inner sides by means of a disk portion 187 of the forwarding wheel and a fixed guide member 188.

In order to accommodate cans of different widths, the said disk 187 is removably attached to the forwarding wheel 188 so that larger or smaller disks may be applied to the forwarding wheel when desired. If desired, the larger disks may be applied to the wheel without removing the smaller disk. In Fig. 4 the large disk 187 is provided with a central opening 189 whereby it may be applied above the smaller disk 190 without removing the head member 182. The guide member 188 is adjustably supported on a vertically disposed member 191. The latter member, in addition to providing a suitable support for the guide member 188, is secured at its upper end to the fixed cam member 164 and thereby provides additional support for said cam.

The cans are discharged from the rotating table by means of arms 179^a of a forwarding wheel 174^a secured to a vertical shaft 181^a. This forwarding wheel is of the same construction as the forwarding wheel 174 and operates to engage the cans successively and slide them from the rotating table onto a conveyor 192, which car-

ries them to a suitable location where they may be packed into crates or other suitable containers. The forwarding wheels 174—174^a and the conveyors 173—192 are operated from driving connections with the large gear 122 of the rotating table. This driving connection consists of pinions 193—194 secured to the vertical shafts of the forwarding wheels and meshing with the large gear 122. The vertical shaft 181^a of the 5 forwarding wheel 174^a is provided with a bevel gear 196 which meshes with bevel gear 197 on a horizontal shaft 198. The shaft 198 carries spiral pinions 199—200 which mesh with spiral gears 201—202 respectively, fixed to the horizontal 10 shafts 203—204 of the driving sprockets of the said conveyors.

In operation the cans together with the pouring spout structures are placed upon the feeding conveyor whereupon they are moved forward by 15 the conveyor chain 173. When they are passed through the forwarding wheel 174 the spouts of the cans are engaged by the fixed cam member 188, thereby moving the spouts into their proper 20 positions. This movement of the cans brings the 25 cup portion of the successive spout structure beneath one of the expanding tools at a location immediately prior to the movement of such tool off the inclined portion 163^a of the trackway 161. This downward movement of the expanding tool 30 moves the pendant dies into the spout structure of the can. The pendant dies are held in this position by the pressure of the coiled springs 157^a while the plunger 157 is given a further downward movement by means of the cam member 164. As soon as a spout structure has been 35 expanded into rigid engagement with a can, the roller 159 of the operated expanding tool moves from beneath the cam 164, whereupon the spring 157^a will cause the plunger 157 of such tool to move upwardly to substantially the position 40 shown in Fig. 5. Further rotation of the table and expanding tools brings the rollers 160 of the several expanding tools onto the inclined end portion 163^b of the trackway 161 thereby raising 45 the plungers 157 and permitting the spring 149 to retract the die sections so as to permit them to be withdrawn from the spout structure. The pendant dies are withdrawn from the spout structure by reason of the lost motion connection of 50 the die carrier 143 with the plunger 157. For example, the first upward movement of the plunger 157 on the inclined portion 163^b of the trackway 161 permits the pendant dies to retract. Further upward movement brings the 55 lower portion of the slot 155 in the plunger against the stop screw 156 thereby causing the die carrier and pendant dies to move upwardly with the plunger 157 during any further upward movement thereof. This movement withdraws 60 the pendant dies from the spout structure so as to permit the cans to be removed from the rotating table when they reach a position adjacent the forwarding wheel 174^a. The arms of said wheel engage the cans successively and slide them onto the discharge conveyor 192.

65 I claim:

1. Apparatus for attaching pouring spouts to

cans comprising in combination, a revoluble table, a plurality of expanding tools arranged in spaced relation above said table, a centrally disposed shaft, a tubular shaft rotatable on the central shaft, means on the tubular shaft for supporting said expanding tools, means on the tubular shaft and slidably engaging the table for connecting said tubular shaft with the revoluble table, means on the central shaft for raising and lowering the expanding tools, means for holding 10 said central shaft against rotation, and means for vertically adjusting the central and tubular shafts relative to said table.

2. Apparatus for attaching pouring spouts to cans comprising in combination, a revoluble table, a plurality of expanding tools arranged in spaced relation above said table, a central shaft, a tubular shaft rotatably supported on the central shaft, means on the tubular shaft for supporting said expanding tools, means comprising 15 an arm on the tubular shaft having a vertically slidable connection with the table, whereby the tubular shaft and expanding tools will rotate in unison with the said table but with capacity for vertical movement of said shaft with relation to 20 said table, means on the central shaft for operating said expanding tools, and means for vertically adjusting said shafts and expanding tools 25 relative to said table to accommodate cans of different height.

3. Apparatus for attaching pouring spouts to cans comprising in combination, a revoluble table, a plurality of expanding tools arranged in spaced relation above said table, a central shaft the lower end of which is formed with screw 35 threads, a tubular shaft rotatably supported on the central shaft, means on the tubular shaft for supporting said expanding tools, means comprising an arm on the tubular shaft having a vertically slidable connection with the table whereby 40 the tubular shaft and expanding tools will rotate in unison with said table but with capacity for vertical movement of said shaft with relation to said table, means on the central shaft for operating said expanding tools, and means for vertically adjusting said shafts and expanding tools 45 relative to said table comprising a nut on the threaded portion of the central shaft, and means for holding the central shaft against rotation 50 whereby rotation of said nut imparts vertical movement to said central and tubular shafts.

4. A machine for securing spout structures to sheet metal cans comprising in combination, a revoluble table for receiving successive cans on which the spout structures are loosely supported, expanding tools movable with said table and adapted to be raised and lowered relative to said cans, forwarding means for moving successive cans onto said table and positioning them beneath said expanding tools, and spout adjusting means 55 positioned to engage said spout structures during the movement of the cans onto said table, to rotate said spout structures into predetermined angular positions on the cans.

65 GEORGE W. CHALMERS.
